UNITED STATES PATENT OFFICE.

WALTER J. HAACK, OF RACINE, MINNESOTA.

DISPENSING MACHINE FOR BOTTLED MILK.

Application filed August 28, 1925. Serial No. 53,172.

This invention relates to a dispensing machine of the coin-controlled type and, while the invention is capable of application for dispensing different kinds of articles, it is particularly designed to dispense cylindrical articles such as the cardboard containers used for containing milk and other liquids.

It is an object of this invention to provide a device of simple and efficient construction adapted to contain a large number of articles or receptacles which may be singly dispensed in a simple and easy manner.

It is a further object of the invention to provide such a device comprising a closed casing having therein a rotatable means carrying a plurality of magazines in which the articles to be dispensed are contained, together with means for moving said carrier and projecting and delivering one of the articles or receptacles.

It is another object of the invention to provide such a device comprising a rotatable table which carries a plurality of circumferentially spaced cylindrical magazines in which the cylindrical receptacles to be dispensed are disposed in superposed relation.

It is also an object of the invention to provide such a structure as set forth in the preceding paragraph, means being provided for locking said table in position and rotating the same, step by step.

It is still another object of the invention to provide a simple novel and efficient means for ejecting the articles dispensed, for locking the table above mentioned in fixed position, and for rotating said table, step by step.

These and other objects and advantages of the invention will be fully set forth in the following description made in connection with the accompanying drawings in which like reference characters refer to the same parts throughout the different views, and in which

Fig. 1 is a view in elevation of the device; Fig. 2 is a vertical section taken on the line 2—2 of Fig. 1, as indicated by the arrows;

Fig. 3 is a vertical section taken on the line 3—3 of Fig. 2, as indicated by the arrows;

Fig. 4 is a horizontal section taken on the line 4—4 of Fig. 2, as indicated by the arrows;

Fig. 5 is a horizontal sectional view through the machine taken approximately on the line 5—5 of Fig. 2, as indicated by the arrows;

Fig. 6 is a sectional view taken on the line 6—6 of Fig. 5;

Fig. 7 is a vertical section taken on the line 7—7 of Fig. 6, as indicated by the arrows; and

Fig. 8 is a vertical section taken on the line 8—8 of Fig. 6, as indicated by the arrows.

Referring to the drawings, the device comprises a cabinet or casing 15. While this cabinet may be of various forms, in the embodiment of the invention illustrated, the same is shown as rectangular in horizontal cross section and having a flat top and bottom. Said cabinet preferably is constructed of spaced walls 15^a between which is disposed suitable heat insulating material 15^b. The casing or cabinet 15 is also shown as provided with short legs 16 at its bottom by which it is supported upon a suitable surface. The casing 15 is provided with a door to give access to the interior thereof for replenishing the magazines therein and while this door may be variously located and constructed, in the embodiment of the invention illustrated, the same is shown as in the form of a lid 15^c having spaced handles 17 thereon. A partition 18 extends across casing 15 spaced some distance from the bottom thereof, which partition is substantially horizontal but has an offset portion 18^a to accommodate certain operating parts in the casing. The chamber below partition 18 is adapted to form a refrigerating chamber and the same may contain some refrigerating apparatus or medium, such as the ice cake shown as B. The casing 15 is provided at one side with a door 19 opening into the chamber below partition 18, which door will be suitably hinged and provided with a suitable locking mechanism. A platform or plate 19 is also supported in casing 15 upon an angle bar 20 extending across one side of said casing and by spaced bars 21 also extending across said casing.

A bearing block 22 is disposed on the partition 18 and a bearing block 23 is also supported above block 22 on the platform 19. The bearing block 22 supports an anti-friction bearing 24, the upper member of which is secured to a shaft 25 journaled in the blocks 22 and 23 and in platform 19. An upper anti-friction bearing 24 also surrounds shaft 25, the upper member of which is secured to a rotatable table 26, and the lower member of which is supported by the hub of

75

100

105

an arm 54 to be later described. The shaft 24 has secured thereto a beveled gear 27 adapted to mesh with a similar beveled gear 28 secured to a shaft 29 journaled in the bars 21, and also 5 in a bearing block 32 disposed in the wall of the casing 15. The shaft 21 also has secured thereto a disk 30 which is shown as vertically disposed, and the lower end of which extends into the chamber or bracket formed by the 10 offset portions 18^a of partition 18. The shaft 29 also carries, outward of the disk 30, a gear 31. The gear 31 meshes with a smaller gear or pinion 33 secured to a shaft 34 also journaled in block 32 at one side of shaft 29 and 15 the shaft 34 projects outward of the casing 15 and has a crank handle 35 secured thereto. A pawl 36 pivoted to a small block on the inner wall of casing 15 co-operates with the gear 31 so that shaft 34 can be turned only in a clockwise 20 direction by the crank 35. The disk 30 has secured thereto at some distance from its center, a weight member 37 and said disk is provided on its edge with a notch 30^a and is further provided with an opening 30^b illustrated as of rectangular form for a purpose to 25 be later described.

The notch 30^a is adapted to be engaged by the toothed end of a slide member 38 guided in a bracket 40 secured to the inner wall of 30 casing 15, which slide moves through a downwardly inclined narrow coin chute 41 which extends diagonally downward toward slide 38, said chute extending through the wall of casing 15 at its upper end and provided with 35 an open horizontally disposed end outward of said casing. The slide 30 has a slot 38^a therethrough, the upper surface of which is convexly curved to form a cam surface. Said chute below and at the inner side of the slide 40 38 extends into a coin receptacle 42. The chute has an intermediate downwardly curved portion 41^a having a slot in its lower side through which is adapted to project a horizontal side 43 guided in a portion 40^a 45 of bracket 40. The slide 43 is normally held in a retracted position by a tension coiled spring 44 secured to its outer end and to one side of casing 15. Said slide 43 is adapted to be moved, however, by a handle 45 projecting laterally from one side thereof and extending through a horizontal slot 15^a in the wall of casing 15. As shown in Fig. 3, the bracket 40 is also constructed to form the 50 bottom of the chute 41 adjacent slide 43. The table 26 supports a multiplicity of vertically disposed cylindrical magazines 46 and it will be noted that these magazines, as shown 55 in Figs. 2 and 5, project over the edge of said table, said magazines having their lower 60 portions cut away as indicated at 46^a, and also have openings 46^b at their inner radial sides which openings are illustrated as of rectangular shape. Each of the magazines 46 is adapted to receive a plurality of superposed cylindrical articles 47, such as card-

board containers for milk. The table 26 is adapted to be locked in fixed position, and for this purpose the same carries on its lower surfaces a plurality of circumferentially spaced blocks 48, each having a central slot 48^a therein, extending radially of the table 26. A sliding bar 49 is mounted in brackets 50 upstanding from platform 19 and has an upwardly extending projection or tooth 49^a at its outer end adapted to enter the notches 48^a. The bar 49 has a pin 51 extending transversely therethrough and projecting at its sides against which presses one end of a compression coiled spring 52, the other end of said spring contacting the side of one of the brackets 50. Spring 52, therefore, normally tends to move bar 49 and bring tooth 49^a into one of the slots 48^a. The inner end of bar 49 is adapted to be contacted by a cam member 53 having an outer curved cam face, which member 53 projects from an arm 54 having a hub keyed to the shaft 25. Arm 54 also carries an outer hub in which is vertically slidably a pin 55. The pin 55 is adapted to be raised at intervals by a cam projection 19^a mounted on platform 19. The table 26 is provided with a series of circumferentially spaced holes 26^a, said table being cut away at the lower side of said holes to form slots 26^b having inclined upper surfaces, as shown in Fig. 8. 90

The upper end of shaft 25, above table 26, has secured thereto an arm 56, above which and at the outer end of which is pivoted a link 57, the other end of said link being pivotally connected to and beneath a plunger 58 spaced some distance therefrom. The plunger 58 is mounted for sliding movement in a depending portion 59^a of a bracket 59 extending across the bottom of lid 15^c and having downwardly extending portions at its side secured to the inner walls of casing 15, the portion 59^c being illustrated as having spaced sides for the greater portion of its length. The plunger 58 is provided with a head 58^a having a concave forward portion and it will be noted that the central longitudinal axis of plunger 58 is radial with table 26 and that said concave portion of plunger head 58^a is concentric with the center of one of the magazines 46 when in the position shown in Fig. 4. 100

A chute 60 is provided having substantially vertically extending sides, the inner edge of which extends in close proximity to the edge of the table 26 and beneath the bottom of the magazine 46. Said chute 60 has an outer portion 60^a, the inner and outer portions of said chute terminating in close proximity to the sides of disk 30 and being adapted to aline with the opening 30^b therethrough when the parts are in the position shown in Figs. 2, 3 and 4. The outer portion 60^a of said chute extends to and alines with an opening 15^c in the side of casing 15, which 110

opening normally is closed by a door 61 hinged about a horizontal axis to a bracket 62 secured to casing 15 above opening 15^e and having an operating handle 63.

5 A counter device 64 is secured to one side of casing 15 and has an operating shaft 65 projecting into said casing, which shaft carries a small pulley 66 held in frictional operating engagement with the edge of disk 30.

10 In operation, the lid 15^e will be removed and the magazine 46 will be filled with the articles or receptacles 47. It will be understood that the lid 15^e normally will be securely locked in closed position. The parts 15 normally will occupy the position shown in the drawings in Figs. 1 to 4. When it is desired to secure one of the articles 47, such as a carton of milk, the operator will insert a coin of the proper dimension which designation 20 will be indicated by an inscription on the apparatus, into the chute 41. The coin will roll down said chute and take the position indicated by coin 67 in Fig. 3. The operator now takes hold of handle 45 and moves 25 the same to the right, as shown in Fig. 1, in the slot 15^a. This moves horizontal slide 43 against the tension of spring 44 and this slide pushes coin 67 into the opening 38^a of vertical slide 38. The coin engages the cam surface 30 at the top of opening 38^a and slide 38 is cammed upwardly so that the tooth at the lower end is moved out of slot 30^a. When this occurs, the weight 37 which normally is in the position shown in Fig. 3, moves 35 downwardly revolving disk 30 so that when the handle 45 is released the slide 38 cannot again enter notch 30^a. The operator, after passing the handle 45 to the right releases the same and then rotates crank handle 35.

40 Upon releasing of handle 45 spring 44 retracts the same and slide 43 to normal position. Crank handle 35, as stated, must be rotated in a clockwise direction. Rotation of crank handle 35 rotates gears 33 and 31, shaft 29, and through gears 27 and 28, shaft 25. Arm 54 is thus turned and the cam 53 moved against the inner end of plunger slide 49 moving tooth 49^a out of the slot 48^a in which it has been engaged. As arm 54 is 45 thus rotated, pin 55 moves upwardly on cam 19^a. When tooth 49^a is moved out of slot 48^a, pin 55 encounters the end of vertical wall of the slot 26^b and one of the holes 26^a and begins to rotate table 26 which rotates on the 50 upper anti-friction bearing 24. The rotation of table 26 continues until pin 55 moves off of cam 19^a, when said pin drops out of the slot 26^b and ceases to operate said table. At this time the next notch 48^e will be brought into 55 alinement with tooth 49^a and spring 52 again moves tooth 49^a into said slot. The shaft 25 makes a complete rotation and, during this rotation arm 56, through its link 57, moves forward the plunger 58. This plunger 58 moves outwardly its head 58^a, engages one

of the articles or receptacles 47 in one of the magazines 46, and as said magazine is in alinement with chute 60, said plunger reaches its outmost position. The article or receptacle 47 is thus pushed off of table 26 and slides down into chute 60, against disk 30. When opening 30^b becomes alined with said chute upon further rotation of disk 30, said article will pass into the outer portion 60^a of said chute. The operator can now lift door 61 70 and remove the article 47, it being noted that crank 35 is out of alinement with said door at this time. As the disk 30 is rotated, the slide 38 will again engage notch 30^a and further rotation of crank 35 in said disk is prevented until another coin is placed in the machine. The rotation of the disk 30 operates the counter 66 which is suitably adjusted to correctly count the number of operations. As stated, the interior of casing 15 is 80 kept at a low temperature by the refrigerating medium, such as the ice B which can be placed therein through the door 19.

From the above description it is seen that applicant has provided an extremely simple and efficient dispensing means and one which has a high degree of utility for storing and dispensing milk or other liquids in cartons. The machine is quite simple in construction and requires few manipulations by the operator. The machine is such that it can be easily transported and placed at the desired locations. The machine can be located in factories, office buildings, and similar establishments so that a large number of people 90 can easily and quickly secure a bottle of milk or other liquid therefrom. The milk or liquid will be contained in cardboard or paper receptacles which may be discarded after use. It will thus not be necessary to have an attendant at the machine and the owner of the machine will only have to replenish the same at intervals and collect the money which is being deposited in the coin receptacle 42. The machine, of course, will have thereon 100 an inscription on a plate, or otherwise, directing the operator how to manipulate the handle 45 and crank 55 after placing a coin in chute 41.

It will, of course, be understood, that various changes may be made in the form, details, arrangement and proportions of the parts without departing from the scope of applicant's invention, which, generally stated, consists in a device capable of carrying out the objects above set forth, in the novel parts and combinations of parts disclosed and defined in the appended claims.

What is claimed is:

1. A dispensing machine of the character described, having in combination a casing, a rotatable table thereon, a plurality of magazines carried by said table, each of said magazines being adapted to contain a plurality of articles to be dispensed, a delivery chute, 125

a mechanism for locking said table in fixed position, a rotatable disk normally adapted to close said delivery chute, but having an opening therein for the discharge of the articles to be dispensed when said disk and said table are rotated to a certain predetermined position, and means for rotating said table and disk and pushing an article from said mechanism into said chute.

10 2. A dispensing machine of the character described having in combination, a casing, a rotatable table therein, a plurality of vertical magazines equally and circumferentially spaced and supported on said table, each adapted to contain a plurality of superposed articles and each magazine having radially aligned openings at its lower end, a delivery means, means for rotating said table to align one of said magazines with said delivery means, an ejecting means operated by said rotating means including a plunger adapted to move through said opening in said magazine and push an article into said delivery means.

15 3. A dispensing machine of the character described having in combination, a casing, a rotatable table therein, a plurality of magazines carried by said table, a delivery means, a cam-controlled mechanism for turning said table comprising a shaft about which said table rotates, an arm secured to said shaft having a cam therein, and a reciprocable member movable therein, spaced apertures in said table adapted to be successively engaged by said reciprocable member, a cam adapted 20 to be engaged by said pin to move the same, and a spring-pressed locking member for said table adapted to be engaged and moved to inoperative position by said cam on said arm.

25 4. A dispensing machine of the character described having in combination a casing, a rotatable carrier therein, a plurality of circumferentially spaced magazines supported on said carrier, each adapted to contain a plurality of articles to be dispensed, means for rotating said carrier, a delivery chute, means for holding said carrier in position with a magazine aligned with said delivery chute, a rotatable disk normally adapted to cut off communication between the magazines, and the delivery end of said chute, said disk being rotatable and having an opening therein adapted to be aligned with said delivery chute to permit of an article being ejected therethrough, and means for pushing an article from said magazine through said opening in said disk and into the discharge portion of said chute.

30 5. A dispensing machine of the character described having in combination a casing, a rotatable table therein, a plurality of magazines carried by said table, a fixed delivery chute extending from said table, means for aligning successive magazines with said chute, a disk having an aperture therein, said disk being adapted to be rotated to align

said aperture with said chute and with the particular magazine opposite the chute, said chute having portions disposed at either side of said disk, and means for pushing an article from the aligned magazine into the adjacent portion of said chute, whereupon the article will fall through the aperture in said disk and into the outer portion of said chute.

35 6. A vending machine having in combination a carrier having a plurality of magazines at a plurality of circumferential equally spaced positions therein, each of said magazines being adapted to hold a plurality of superposed articles, means operating said carrier from said shaft to turn said carrier the distance between adjacent magazines during one complete revolution of said shaft, a fixed chute which is always adapted to face one of said magazines when said carrier is at rest, and means operated by said shaft for pushing out upon said chute during the complete revolution of said shaft, the lowermost article held in the particular magazine opposite said chute.

40 7. The structure defined in claim 6 and a revolvable disk between the outer portion of said chute and the magazines on said carrier, said disk being revolvable with said shaft and having an aperture therethrough to permit passage of an article to the outer portion of said chute when said aperture is aligned therewith.

45 8. A dispensing machine of the character described having in combination a casing, a circular carrier having a plurality of magazines at a plurality of circumferential equally spaced positions thereon, each of said magazines being adapted to contain a plurality of superposed articles, a rotatable shaft, means operated by said shaft for rotating said carrier a distance equal to the distance between adjacent magazines on said carrier during every complete revolution of said shaft, a fixed chute outward from said magazine and a push arm operated by said shaft to push the lowermost article in one of said magazines into said chute during one complete rotation of said shaft.

50 9. A dispensing machine of the class described having in combination a casing, a rotatable table thereon, a plurality of equally spaced magazines carried by said table and adapted to contain a plurality of superposed articles, a shaft about which said table turns, means normally holding said table in locked non-rotating position, means carried by said shaft for engaging said first mentioned means to unlock said table therefrom, means for simultaneously engaging said table to permit the same being turned with said shaft a distance equal to the distance between magazines, a chute with which a magazine is always adapted to be aligned when said table is at rest, and an ejecting means operated by said shaft and adapted to eject one of the

articles from an aligned magazine into said chute during a complete revolution of said shaft.

10. A dispensing machine of the class described having in combination a casing, a rotatable table therein, a plurality of magazines carried by said table, a delivery means, means for rotating said table and an eject-

ing mechanism including a plunger, an arm rotatable with said table and a link connecting said arm and said plunger, said ejecting means being adapted to eject an article from one of said magazines as said table is rotated. 10

In testimony whereof I affix my signature.
WALTER J. HAACK.
